UNITED STATES PATENT OFFICE

WALTER VON NESSEN, OF NEW YORK, N. Y., ASSIGNOR TO EFCOLITE CORPORATION, OF TRENTON, NEW JERSEY

DESIGN FOR A LIGHTING FIXTURE OR ARTICLE OF SIMILAR NATURE

Application filed March 21, 1931. Serial No. 39,190. Term of patent 7 years.

To all whom it may concern:

Be it known that I, WALTER VON NESSEN, a citizen of Germany, residing in New York, in the county of New York and State of New York, have invented a new, original, and ornamental Design for a Lighting Fixture or Article of Similar Nature, of which the following is a specification, reference being had to the accompanying drawings, forming a part thereof.

Figure 1 is a front elevational view of a lighting fixture showing my new design.

Fig. 2 is a side elevational view thereof.

Fig. 3 is a top plan view thereof.

I claim:

The ornamental design for a lighting fixture, or article of similar nature, as shown.

In testimony whereof I affix my signature.

WALTER VON NESSEN.
